FREDERICK G. KEYES, OF BOSTON, MASSACHUSETTS, ASSIGNOR TO COOPER HEWITT ELECTRIC COMPANY, OF HOBOKEN, NEW JERSEY, A CORPORATION OF NEW JERSEY.

MERCURY-VAPOR APPARATUS.

1,078,859.

Specification of Letters Patent. Patented Nov. 18, 1913.

Application filed February 11, 1913. Serial No. 747,587.

To all whom it may concern:

Be it known that I, FREDERICK G. KEYES, a citizen of the United States, and resident of Boston, county of Suffolk, State of Massachusetts, have invented certain new and useful Improvements in Mercury-Vapor Apparatus, of which the following is a specification.

My invention relates to mercury vapor lamps adapted to operate on the principle of the well-known Cooper Hewitt lamps and more particularly to lamps of this class operating at high temperatures or pressures.

With the apparatus hereinafter described I have shown a structure having two electrodes of vaporizable material and having the property of automatically maintaining the proper distribution of the electrode material between the electrodes during normal operation without the physical transfer of electrode material in liquid form from one electrode to the other.

My apparatus is an improvement on certain other devices intended to serve a similar function.

This feature and certain others are shown in the drawings of this specification or are described in the specification.

Figure 1 represents a side elevation of the lamp embodied in my invention and Fig. 2 shows a plan view of the same lamp. Fig. 3 shows in some detail a seal for a quartz container suitable for permitting the entrance of electric current within the vacuum space.

In Fig. 1, I show a container having a light giving portion, 1, an anode condensing chamber, 2, a cathode cooling chamber, 3, and seals, 9. This container is frequently made of transparent or partially transparent silica or fused quartz, though other materials such as a relatively high melting glass may be used without departing from my invention.

The anode is shown as of mercury at 4 and the cathode as a large body of mercury at 5, having a small active electrode surface at 6. The seal, 9, which I constitute of a platinum cup, 14, carrying a rod, 10, both inside and outside the container, gives a hermetically tight joint and transmits with ease any current required for this device.

The details of the seal may be varied, or any preferred form of seal may be substi-

tuted for that shown herein, it being only necessary that the seal should be and remain gas-tight and should afford means for good electrical connection between the external circuit and the inside lamp electrodes.

At the cathode end of the container I utilize a funnel-shaped tube, closely fitted to or integral with the adjacent end of the main tubular portion giving and dipping at its small end under the surface of the mercury, 5, in the cathode chamber, 3. The operation of this device is as follows: The current passes, according to the old convention as to direction from the anode, 4, to the cathode, 6, generating heat in the electrodes and the vapor path. As is well known the electrodes are both heated and mercury vaporized to maintain a relatively high pressure throughout the exhausted space. This produces a high voltage drop in the current path and a very high temperature in the vapor thereabout which in turn heats the adjacent tubular portion of the container to a temperature which is high in comparison with the electrode temperature.

A portion of the heat generated by the current is dissipated from the positive anode condensing chamber, 2, to which it is carried by the mercury vapor. A portion of the heat generated is also dissipated at the cathode chamber, 3, and it is desirable that the amounts of heat so dissipated be proportioned more or less in the same ratio as the heat generated at the two electrodes respectively. If this condition be accurately attained there would be no permanent transfer of mercury from one electrode to the other. Since, however, this condition can not, in practice, be permanently produced by the mere initial proportioning of the cooling surface of the anode condensing chamber and the electrode chamber, it is usually desirable to have some supplemental, automatic, or self-adjusting means for maintaining the exact proportionality required. Such a means is supplied by the funnel-shaped piece, 12.

The functioning of this device is as follows: At the instant of starting, the cathode chamber will be entirely filled owing to the tipping of the lamp, if we assume this lamp to be started by tipping. The arc having started, the heat communicated to the funnel-shaped piece causes

evaporation of cathode material and consequent transfer of cathode material to the anode chamber. When equilibrium is finally attained, it will be found that the mercury meniscus in the funnel-shaped tube is depressed and locates near the lower end of the tube and also a small free space appears in the cathode chamber. The meniscus in general will stop at the lower end, 10 owing to the fact that the heat is then more readily communicated to the cathode material.

In operation, mercury vapor sometimes depresses the meniscus within the funnel-shaped piece to such an extent that vapor bubbles into the cathode chamber and condenses there. This action causes the agitation of the mercury within the cathode chamber and serves two purposes; first, the 20 mercury being in contact with the funnel-shaped piece inside the cathode chamber, serves to keep the latter comparatively cool, thus retarding the disintegration of said funnel-shaped piece; and, second, it is obvious that the agitation of the mercury in the cathode chamber incident to this bubbling of the vapor mentioned, tends to cause a more rapid equalization of temperature throughout the mass of mercury and 30 hence a more rapid dissipation of heat.

While I do not wish to make a definite conclusion as to the theory as to why equilibrium is attained when the mercury level within the tube becomes depressed to the point indicated, it appears to be related to the variations produced in the heat dissipating capacity of the cathode chamber with variations in the level and freedom of entrance of mercury vapor into the cathode 40 chamber from the main tubular portion. The amount of heating of this tube can be controlled by varying the thickness of the tubular portion of the piece 12, which varies the capacity thereof for conducting heat to the mercury 5. A rather heavy wall 45 is sometimes found desirable at this point.

In Fig. 2 are shown in plan the same elements that are shown in Fig. 1, similar reference characters being used. I may add 50 that the part 11 is a trough formed in the container to expose in the direction toward the cathode only a narrow anode surface so that the motion of the end of the current path is restricted and flickering is reduced. 55 It is generally desirable to thicken the material of the container just above the anode as at the point, 7, which is a point of relatively high temperature. I frequently provide a ring or ridge, 8, around the seal 60 chambers to facilitate the securing of a cap for protecting the leading-in wires and mechanically supporting the external lead.

In Fig. 3 the seal chamber is shown enlarged, 16 representing an extension of the 65 container with the rim or ridge 8 utilized

for securing the seal cap. At 14 I use a small very thin platinum cup, or tube, closed at one end. The thickness of this may not exceed one or two thousandths of an inch in some cases. When the container 70 is made of quartz, in order to produce a safe and tight connection between the wall of the container and the platinum tube I use an intermediate section, 13, of the seal chamber made of material capable of making a tight joint with the wall of the part 16, and also with the thin platinum cup 14. For this material I may use a glass made of a glass mixture of quartz with a portion of some other glass capable of being joined to 80 fused quartz. This may be formed by melting together one part magnesium borate and about twenty parts of ground fused silica. This produces a material which can be sealed to quartz and which also will adhere 85 to platinum when formed as here shown. When the glass is shaped into a cylinder as shown at 15 and melted about the thin platinum tube, the platinum tube will be somewhat stretched on the cooling down after 90 the formation of the seal. In operation this stretching is somewhat relieved by the heating up of the seal chamber. In this connection it should be stated that the thickness of the platinum should be so adjusted that 95 cohesion between the metal and the glass persists when the seal is cooled down. It is often desirable to utilize in the hollow of the closed tube, 14, a conducting rod, such as shown at 10 in Fig. 1 and a similar 10 rod, or connection may be attached to the outside of the platinum by silver solder or other means.

While I have shown and described a certain specific apparatus embodying my invention, I do not wish to limit its use to these special structures, but contemplate that any apparatus producing the advantageous results of this invention by equivalent means may come within its scope. For 10 example other materials than mercury may be used for electrodes, devices may be operated at other temperatures, or for various purposes including illumination, other seals may be used, other forms of anode condensing chamber or cathode chambers and so on. 11

Instead of using fused quartz for the body of the container I may employ glass having a high-melting-point or a combination of such high-melting-point glass and 12 fused silica.

I claim as my invention:

1. A vapor electric apparatus comprising a tubular portion, an anode of mercury at one end thereof, a condensing chamber in 12 the neighborhood of and draining into said anode, a cathode at the other end of said tubular portion, a cooling chamber at said cathode and a funnel shaped diaphragm between said cathode chamber and said tubu- 13

lar portion, said funnel shaped piece having its small end dipping under the surface of said cathode.

2. In a vapor electric apparatus having a plurality of liquid electrodes, means for maintaining the normal quantity of electrode material at an electrode, said means comprising a funnel shaped diaphragm traversed by the normal current flow, an active electrode surface within said funnel

shaped diaphragm and means for producing a graduated rise of temperature along said funnel shaped diaphragm.

Signed at New York in the county of New York and State of New York this 7th ¹⁵ day of February, A. D. 1913.
